United States Patent Office

Des. 180,341
Patented May 21, 1957

180,341

PILOTLESS PROPELLER DRIVEN AIRPLANE

James F. Reagan and Marvin J. Gordon, Wichita, Kans.,
assignors to Beech Aircraft Corporation, Wichita, Kans.,
a corporation of Delaware

Application December 8, 1955, Serial No. 39,220

Term of patent 14 years

(Cl. D71—1)

Fig. 1.

Fig. 1 is a plan view of the pilotless propeller driven airplane embodying our new design;

Fig. 2 is a side elevation; and

Fig. 3 is a front view of the same.

The essential features of our design reside in the portions shown in full lines.

We claim:

The ornamental design for a pilotless propeller driven airplane, substantially as shown and described.
